George M. Fiero,

INVENTOR

William Thompson

BY Victor J. Evans

ATTORNEY

WITNESS:

UNITED STATES PATENT OFFICE

GEORGE M. FIERO, OF PITTSBURGH, PENNSYLVANIA

TIE RAIL CLAMP

Application filed January 24, 1930. Serial No. 423,203.

This invention relates to a rail clamp, the general object of the invention being to provide clamps for holding a rail to a tie so as to prevent the spikes which connect the rail 5 with the tie from working loose and causing the rail to spread or upset.

This invention also consists in certain other features of construction and in the combination and arrangement of the several 10 parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a perspective view showing a 20 portion of a rail and tie, with the clamp in position.

Figure 2 is an elevation of the rail and a section through the tie.

In these views, the letter A indicates a 25 rail and B a tie, the rail being connected with the tie by the usual spikes.

In carrying out my invention, I provide hook shaped clamps 1, one of which has its hook part engaging the base of the rail at 30 one side thereof and the other engages the edge of the base at the opposite side of the tie. These clamps are connected with the tie by the nails 2, a pair of nails being used for connecting each clamp to the tie, so that 35 there is no danger of the clamp pivoting on the tie. Thus the rail is connected with the tie by a pair of the clamps in addition to the spikes and these clamps prevent movement of the rail relative to the tie, so that there is 40 no danger of the spikes working loose and the spikes and clamps cause the tie to move with the rail.

It is thought from the foregoing description that the advantages and novel features 45 of the invention will be readily apparent.

It is to be understood that changes may be made in the construction and in the combination and arrangement of the several parts, provided that such changes fall within 50 the scope of the appended claim.

What I claim is:

In combination with a rail and a tie, a pair of plate-like clamps, each having an elongated body, with a hook extending laterally from one end thereof and each plate 55 having a pair of perforations therein, whereby one plate can be fastened to one side of a tie by fastening means driven through the perforations with its hook engaging an edge of the base of the rail and 60 the other clamp can be fastened to the opposite side of the tie with its hook engaging the opposite edge of the base of the rail.

In testimony whereof I affix my signature.
